Attorney.

UNITED STATES PATENT OFFICE.

EUGENE WARREN WILSON, OF DETROIT, MICHIGAN, ASSIGNOR OF ONE-HALF TO
WILLIAM CLIFTON MORGAN, OF HIGHLAND PARK, MICHIGAN.

SANITARY SHAVING-CUP.

1,138,825.

Specification of Letters Patent.

Patented May 11, 1915.

Application filed January 13, 1913. Serial No. 741,716.

To all whom it may concern:

Be it known that I, EUGENE WARREN WILSON, a citizen of the United States, residing at Detroit, county of Wayne, State of Michigan, have invented a certain new and useful Improvement in Sanitary Shaving-Cups, and declare the following to be a full, clear, and exact description of the same, such as will enable others skilled in the art to which it pertains to make and use the same, reference being had to the accompanying drawings, which form a part of this specification.

This invention relates to sanitary shaving cups and an object thereof is a cup in which a lather is formed for use in shaving that may be thoroughly cleansed after each use and the possibility of the transfer of disease germs accumulated by previous use thus avoided and thereby peculiarly adapting the device for use in barber shops or wherever a single cup is used in shaving a number of persons.

Another object is a device of the character stated in which the loss of soap from the cleansing operation is reduced to the minimum as the soap required in a single operation may be practically automatically supplied in the desired quantity, and a further object is in the provision of means for holding the shaving brush in such manner that the bristles remain substantially in a straight line thereby preventing a distortion thereof ordinarily resulting from allowing the brush to rest in the bottom of the cup under which condition the bristles conform to the shape of the cup.

These and further objects and novelties of the invention are hereinafter more fully described and claimed and shown in the accompanying drawings in which—

Figure 1 is a perspective view of a shaving cup embodying my invention. Fig. 2 is a vertical section thereof. Fig. 3 is an enlarged detail of a portion of the device more fully showing the valve controlling the passageway between the soap chamber and the lather chamber.

Similar characters refer to similar parts throughout the drawings and specification.

The cup may be formed of any desirable material, as metal, glass, or earthenware, and consists of a body portion 1 within which is formed a lather chamber 2 the walls of which are spaced from the outer

wall of the body providing a chamber 3 therebetween for a liquid soap or other lather-producing solution. This chamber 3 preferably surrounds the lather chamber 2 and is provided with a filling opening normally closed by a screw 4 or similar device for the purpose. Also leading from the chamber 3 to the chamber 2 is a passageway 5 normally closed by the pivotally supported valve 6 for which purpose a spring 7 presses against one end of a lever to which the valve is attached tending to maintain the valve in the closed position. To this valve lever is also attached a vertically positioned operating stem 8 passing through the upper wall of the solution chamber and terminating in a conveniently positioned operating button 9. The stem 8 is also provided with a valve 10 normally closing the opening 11 in the chamber wall through which the stem passes and the spring 7, therefore acts in a manner to hold both valves on the seats provided and the device may be held in any position without the possibility of a loss of solution. When the button 9 is depressed to open the passageway 5 between the solution chamber and the lather chamber to allow a portion of the solution to flow into the lather chamber, the valve 10 is also depressed which allows air to flow into the solution chamber through the aperture in which the stem is positioned which allows the lather solution to flow freely.

Attached in any convenient manner, as to a portion of the handle of the cup as shown, is a brush supporting stirrup 12 preferably pivoted to the handle between the prongs of which the brush may be held when not in use and this support or stirrup may be turned on its pivot as shown by dotted lines in Fig. 2 so as not to project over the chamber 2 and the opening thereof is free of obstruction when in use.

The passageway 5 leading from the chamber 3 to the chamber 2 is preferably located near the lower end of the chambers in order that the solution may be as nearly completely emptied as possible by the natural flow of the liquid when the valve 6 is open.

In operation the valve 6 is opened, as is also the valve 10, by depressing the button 9 whereupon any desired amount of solution in the chamber 3 may flow into the chamber 2 through the passageway 5 and the valves

then closed by the action of the spring 7 upon the release of the button 9. Hot water may then be added to the solution and the brush used to work the solution into a lather 5 and after the use of the lather in the usual manner in shaving the brush and brush chamber 2 may be washed and thoroughly cleansed by any desirable antiseptic solution without the loss of lather solution other 10 than what may remain in the lather or brush-chamber 2 as the valves are at this time closed. This operation is repeated in the shaving of other individuals.

From the foregoing description it becomes 15 evident that the cup is inexpensive in construction, simple in operation having but few parts which parts do not readily become displaced and that all sanitary requirements in a device of this nature are fully met, and 20 while I have shown a valve operating stem of a peculiar nature, it is to be understood that various means may be employed for this purpose without departing from the 25 spirit of this invention except as limited by the appended claims.

Having thus briefly described my invention and its mode of operation, what I claim and desire to secure by Letters Patent of the United States is—

30 1. In a shaving cup, an open cup-shaped

lather chamber, a lather-producing solution chamber surrounding the lather chamber, said solution chamber being closed to atmosphere with the exception of a vent and a closable opening and closed as to the lather chamber with the exception of a passageway therebetween, the latter chamber being supported at the top and bottom in the solution chamber, said vent and said passageway being normally closed, and means for opening both the vent and the passageway.

2. In a shaving cup, an open cup-shaped lather chamber, a lather-producing solution chamber formed between the wall of the lather chamber and the outer wall of the cup, there being a passageway between said chambers near the bottom of the lather chamber, the solution chamber being otherwise closed to atmosphere with the exception of a vent and a closable opening, a valve normally closing said passageway, a valve normally closing said vent, and means for operating said valves from the exterior of the cup.

55 In testimony whereof, I sign this specification in the presence of two witnesses.

EUGENE WARREN WILSON.
